Attorney

UNITED STATES PATENT OFFICE.

JACOB GOLDBERG, OF CINCINNATI, OHIO, ASSIGNOR TO THE GOLDBERG PADDING MACHINE COMPANY, OF CINCINNATI, OHIO, A CORPORATION OF OHIO.

KNEE LIFTER-PAD FOR SEWING-MACHINES.

1,367,040.

Specification of Letters Patent.

Patented Feb. 1, 1921.

Application filed April 22, 1920. Serial No. 375,726.

To all whom it may concern:

Be it known that I, JACOB GOLDBERG, a citizen of the United States of America, and a resident of Cincinnati, in the county of 5 Hamilton and State of Ohio, have invented a new and useful Improvement in Knee Lifter-Pads for Sewing-Machines, of which the following is a specification.

An object of my invention is to provide 10 a pneumatic knee lifter pad for use with a knee lifter plate employed for operating the presser-foot of a sewing machine for instance such as is shown in the patent to Goldberg No. 1,187,724.

Another object of my invention is to provide 15 a soft contact for an operator's knee when operating a sewing machine, thereby avoiding formation of calli on the knee.

These and other objects are attained by 20 the means described herein and disclosed in the accompanying drawing, in which:—

Figure 1, is a side elevation of a pad embodying my invention, attached to a presser-foot operating lever.

Fig. 2, is a transverse sectional view, on 25 an enlarged scale of a knee lifter pad embodying my invention and mounted on a knee lifter plate.

Fig. 3, is an enlarged end view of a pad 30 embodying my invention, part of the pad being broken away.

My invention comprises an air-filled chamber between layers of rubber and forming 35 a pneumatic pad that may be attached to a lifting plate.

The pad A, comprises an upper layer or 40 pad section a , and a lower layer or pad section a' , of rubber, the outer edges of the sections being united to form a chamber a^2 between them. This chamber a^2 is sealed,

confining the air therein. At several places adjacent to the upper layer a , are formed a series of upwardly and inwardly extending lugs a^3 adapted to engage a knee lifting plate B, and to secure the pad upon such 45 lifter plate.

The rod C is attached to the presser-foot of a sewing machine. When upward pressure is exerted upon the pad A and the plate B, the foot of the machine is pulled up making it possible to feed material to the needle of the machine. Considerable upward pressure is required to pull the foot upward, and calli formed upon that portion of the operator's limb engaging the knee plate B. 50

Having thus described my invention, what I claim is:

1. As a new article of manufacture a pneumatic pad comprising a casing, an air chamber within the casing and means to 60 attach the pad to a lifter plate of a sewing machine.

2. As a new article of manufacture a pneumatic pad comprising an upper and a lower pad section, an air chamber between 65 the pad sections and lugs extending from one of the pad sections, and adapted to engage a lifter plate.

3. As a new article of manufacture a pneumatic pad, the combination of a casing 70 having upper and lower sections united at their outer edges, an air chamber between the casing sections and lugs extending upwardly and inwardly from the outer edge of the pad.

In witness whereof, I have hereunto subscribed by name this 20th day of April, 1920.

JACOB GOLDBERG.
